UNITED STATES PATENT OFFICE.

DAVID CURRY, OF NEW YORK, N. Y.

GUARD FOR PRINTING-PRESSES.

1,351,997.

Specification of Letters Patent. Patented Sept. 7, 1920.

Application filed April 26, 1919. Serial No. 292,818.

To all whom it may concern:

Be it known that I, DAVID CURRY, a citizen of the United States, and a resident of New York, in the county of New York and State 5 of New York, have invented a certain new and useful Improvement in Guards for Printing-PresSES, of which the following is a full, clear, and exact specification.

This invention relates to a class of safety 10 devices adapted to be used in the art of printing.

My invention has for its object primarily to provide a guard or apparatus designed to be employed for protecting a person when 15 feeding a printing press, such as types commonly known as job presses, whereby the person will be prevented from accidental injury to the fingers or hand by being inadvertently moved between the platen and the 20 bed of the press during the period of feeding, and which is adapted to allow sheets of material to be held and removed from the press by the feeder especially when partial printing of the sheets is required. This 25 invention resides mainly in providing a fender adapted to be disposed between the platen and the bed of a printing press, and associated with the fender is mechanism which is operably mounted on the platen so 30 that the fender will be swung toward and from a position in proximity to the bed of the press with the movements of the platen whereby the fender will serve to prevent the person feeding sheets in the press from 35 thoughtlessly directing the fingers and hand between the platen and bed particularly during the printing process when the sheets are removed from the press.

A further object of the invention is to 40 provide a simple, efficient and durable guard for printing presses which may be made in any desired shape and size.

With these and other objects in view the 45 invention will be hereinafter more particularly described with reference to the accompanying drawing forming a part of this specification in which similar characters of reference indicate corresponding parts in all the views, and will then be pointed out in 50 the claims at the end of the description.

In the drawing, Figure 1 is a fragmentary view, partly broken away, showing a side

elevation of a type of printing press with one form of guard embodying my invention applied thereto, and

55

Fig. 2 is a perspective view, partly broken away, of the guard.

The device or guard has a fender or screen 10 which in practice is arranged between the platen, as 11, of a printing press, as 12, 60 having, a bed, as 13, the form of press illustrated being of a well known make used for job printing, and which is constructed so that the bed supports forms of type, as 14, in a vertical position, while the platen is 65 pivotally mounted on a frame, as 15, of the press for being moved by one or more bars, as 16, and one or more drive gears as 17, in a direction to circumscribe a partial circle as well as being moved for a short dis- 70 tance longitudinally toward and from the bed and the type when the press is operated for accomplishing the printing process.

The fender or screen 10 may be of any suitable form, though the fender shown is 75 preferably made of a sheet or apron of cloth, leather or other flexible material in substantially a rectangular shape. The upper lengthwise edge of the fender is held on the central part of a rod 18 of a frame 19 80 also having two side bars 20 and 21, the rod being provided between the upper ends of the side bars. The side bars 20 and 21 are slidably disposed through apertures provided transversely in sleeves, as 22 and 23, 85 having two of their ends in opposition. Protruding toward each other from the opposed ends of the sleeves are pins 24 and 25, and these pins are rotatably disposed in sockets, not shown, one of which is pro- 90 vided in each of the upper parts of the side edges of the platen 11 in proximity to its upper or righthand end. The fender 10 with its frame may, therefore, be moved in upward and downward directions as well as 95 being rotatably swung with respect to the platen. The lower lengthwise edge of the flexible fender or screen 10 is fastened, as at 26, by bolts or otherwise to the edge of the platen 11 which corresponds to the upper 100 end of the vertical bed 13 of the press. On the central parts of the side bars 20 and 21 of the frame 19 are fixed collars 27 and 28, and encircling the parts of the side bars be-

tween the collars and sleeves 22 and 23 are spiral springs 29 and 30 which are tensioned to normally force the side bars yieldingly downward toward the lower end of the 5 platen. Associated with the fender 10 and with the frame 19 is a mechanism, as 31, adapted to be operably mounted on the platen of the press to cause the fender to be swung upwardly and downwardly be- 10 tween the platen and bed of the press as well as toward and from a position in proximity to the bed synchronously with the movements of the platen when the press is operated.

15 The mechanism 31 may be of any suitable type, though the mechanism preferably consists of two similar levers or bars, as 32 and 33, each of somewhat an L-shape to provide two angularly disposed arms 34 and 35. 20 At the intersection of these arms of each of the levers is a sleeve 36, and both of the sleeves are rotatably mounted on fixed pins provided on the lower parts of the sides of the platen 11 of the press. The levers are 25 also arranged on the pins so that their arms 34 are disposed downwardly, while their arms 35 are disposed upwardly toward the lower end of the platen. The arms 34 are somewhat shorter than the arms 35 of the 30 levers, and extending in opposite directions from the free end parts of the arms 34 of the levers are pins or stops, as 37 and 38. By pivoting the L-shaped levers or bars in this manner to the platen the levers may be 35 swung so that their arms 34 will move in directions toward and from the bed of the press, while the arms 35 of the levers will move in directions upwardly and downwardly with relation to the platen. The free 40 ends of the arms 35 of the levers 32 and 33 are rotatably mounted on pins 39 and 40 which protrude from the sleeves 41 and 42 held on the ends of the side bars 20 and 21 of the frame 19 which are opposite to the 45 rod 18. On the opposite parts or exposed faces of the arms 34 of the levers or bars 32 and 33 are provided trips or pawls, as 43 and 44, both of which are of similar formations. Each of the trips or pawls is ap- 50 proximately L-shaped to provide a short arm 45 and a somewhat longer arm 46. The elbows of these pawls are pivoted, at 47 and 48, respectively, to the central parts of the arms 34 of the levers 32 and 33 somewhat 55 above the stops 37 and 38 of the arms 34 and so that the arms 46 of the pawls are disposed vertically downwardly in close proximity to the stops, while the arms 45 of the pawls are disposed transversely toward 60 the bed 13 of the press. To the free ends of the arms 45 of the pawls are held one of the ends of spiral springs 48 and 49, and the second ends of both of the springs are held to the upper parts of the arms 34 of the levers 32 and 33 for normally serving to

cause the pawls to be swung so that their arms 46 will assume normal positions toward the stops 37 and 38 of the levers 32 and 33. On the frame 15 of the press, and in spaced relation to the lower ends of the 70 levers 32 and 33 are provided corresponding brackets, as 50 and 51, and protruding from these brackets are lugs, as 52 and 53. These brackets are arranged on the frame 75 of the press so that their lugs are spaced on transverse alinement from the stops 37 and 38 of the levers 32 and 33 and so that the arms 46 of the spring actuated pawls 43 and 44 are between the stops and the lugs of the brackets.

80 When the press is operated and sheets of paper, as 54, or other material are fed on the platen 11 in the usual manner, the platen with the sheets will be first swung to circumscribe a partial circle toward the bed of the press to positions, as indicated at A and B, and the platen is then moved for a short distance in a longitudinal direction, as at C, to the type 14 of the bed 13.

85 With these movements of the platen the guard mechanism being mounted thereon will move with the platen until arms 46 of the pawls 43 and 44 encounter the fixed stops 52 and 53 compelling arms 32 and 33 to swing on pivots 36 and cause the frame 90 95 19 to be swung upwardly to the position at D. Springs 29 and 30 being thus compressed during the upward movement of levers 32 and 33 and by the further movement of the platen toward the type, that is 100 the movement of the platen from position B to C, the arms 46 of the pawls 43 and 44 slide over the lugs 52 and 53 of the brackets 50 and 51, causing the frame 19 to snap back to the retracted position at E by actuation of the springs 29 and 30 so that the top of the fender is just above the upper part of the type on the bed of the press just at the moment of the impression. Following the printing of the sheets the feeder of the press may readily remove each sheet 105 immediately upon the reversal of the platen movement, that is, from position C to position B. On the return movement of the platen the guard will retain its retracted 110 position and not interfere with the removal of the printed sheet or the feeding of another sheet as the trips 43 and 44 in contacting with the lugs 52 and 53 of the brackets 50 and 51 will be caused to leave 115 their stops 37 and 38 sliding over lugs 52 and 53 without imparting any movement to levers 32 and 33; thus tensioning springs 48 and 49 which cause the pawls to return to 120 their normal positions against the stops 37 and 38 when the platen reaches its maximum outward or feeding position, as shown in Fig. 1.

125 In the foregoing description, I have embodied the preferred form of my invention, 130

but I do not wish to be understood as limiting myself thereto, as I am aware that modifications may be made therein without departing from the principle or sacrificing any of the advantages of this invention, therefore, I reserve to myself the right to make such changes as fairly fall within the scope thereof.

Having thus described my invention, I claim as new and desire to secure by Letters Patent:—

1. In a guard for a printing press having a vertically disposed type bed and having a platen operably movable toward and from the type bed, the combination with a frame slidably and pivotally mounted on the sides of the platen, of a flexible screen held to the frame and held to the platen for being adjusted upwardly and downwardly relative to the top of the platen, levers mounted on the platen for raising the frame, carrying pawls whereby the levers may be tripped near the closing movement of the platen, and springs for causing retracted adjustment of the frame and screen.

2. In a guard for a printing press having a vertically disposed type bed and having a platen operably movable toward and from the type bed, the combination with a frame slidably and pivotally mounted on the sides of the platen, of a flexible screen

held to the frame and held to the platen for being adjusted upwardly and downwardly relative to the top of the platen, levers mounted on the platen for raising the frame, 35 and trips carried by the levers whereby the levers may be tripped near the closing movements of the platen, and springs for causing retracted adjustment of the frame and screen.

3. In a guard for a printing press having a vertically disposed type bed and having a platen operably movable toward and from the type bed, the combination with a frame slidably and pivotally mounted on 40 the sides of the platen, of a flexible screen held to the frame and held to the platen for being adjusted upwardly and downwardly relative to the top of the platen, levers mounted on the platen for raising 45 the frame, stops on the frame of the press, and pawls carried by the levers for contacting with the stops whereby the levers will be tripped near the closing movement of the platen and springs for causing retracted adjustment of the frame and screen. 50 55

This specification signed and witnessed this 25th day of April A. D. 1919.

DAVID CURRY.
